(57) CLAIM

The ornamental design for a digital audio player, as shown and described.

DESCRIPTION

FIG. 1 is a front elevational view of a digital audio player showing my new design;

FIG. 2 is a rear elevational view thereof;

FIG. 3 is an enlarged left side elevational view thereof, without the card;

FIG. 4 is an enlarged right side elevational view thereof, without the card;

FIG. 5 is an enlarged perspective view thereof, without the card; and,

FIG. 6 is an enlarged perspective view thereof, with the card. The broken lines showing the headphones and attachments are for illustrative purposes only and form no part of the claimed design.

The right and left sides of the headphones shown in FIGS. 1–2 form no part of the claimed design.

1 Claim, 6 Drawing Sheets
